CONVEYER

John B. Brennen, Atlanta, Ga.

Application January 17, 1940, Serial No. 314,339

10 Claims.

(Cl. 19—79)

Generically this invention relates to cotton feed hoppers and conveyers for conveying the cotton therefrom but it is more especially directed to an endless belt type of conveyer.

Conveyers of this general type heretofore in use in the nature of elevating aprons or conveyers are generally constructed of wood slats fitted with steel pins or spikes mounted on leather carrier belts and which constructions present many disadvantages. Considerable stress and strain is transmitted to the pins, slats and belt by reason of the initial separation of quantities of cotton from the hopper bulk and the surplus carried to and returned by the doffing roll or cleaning mechanism at the upper end of the conveyer, which in many instances causes breaking or dislodging of the slats, loosening of the pins and stretching of the belt, all of which contribute to quick deterioration of the conveyer structure and slowing up of the operation of the machinery and, therefore, one of the important objects of this invention is the provision of an endless belt conveyer structure constructed entirely of metal, which not only prevents stretching of the belt, breaking of the slats, and dislodging and breaking of the pins or spikes, but obviates the fire hazard incident to the creation of sparks by the broken portions coming in contact with the moving parts of the machinery.

One of the principal objects of this invention is the provision of a cotton elevating conveyer comprising detachable teeth elements and means for locking the teeth in operative position, the construction of said teeth and locking means being such as to withstand the stresses incident to the cotton elevating operation without breakage of or damage to the teeth.

An important object of this invention is the provision of an endless metallic elevating belt or apron, non-stretchable in character and adapted to eliminate the fire hazard present in types heretofore in use, the construction of the picker teeth and supporting means being such as to permit the expeditious mounting and removal of said teeth and adapted to co-operate with the doffing or cleaning devices to deliver a uniform distribution of the cotton from the conveyer.

A still further important object of this invention is the provision of an endless conveyer belt or apron for cotton handling machines including detachable teeth and mountings therefor, said teeth being formed with an extended base adapted to brace said teeth in the direction of their pull, the free or sharp ends extending at an angle with respect to the body of the teeth, thereby permitting a better engagement of the teeth with the cotton bulk and separation of the desired amount therefrom and permitting the

doffing mechanism to remove only the surplus for return to the bulk, leaving more uniform quantities on the teeth and permitting a more efficacious stripping of the teeth by the associated stripper mechanism, thereby insuring a more even distribution of the cotton from the conveyer.

With these and other objects in view, which will become apparent as the description proceeds, the invention resides in the construction, combination and arrangement of parts, hereinafter more fully described and claimed, and illustrated in the accompanying drawing, in which like characters of reference indicate like parts, throughout the several figures, of which:

Fig. 1 is a sectional view somewhat diagrammatic through a cotton hopper showing the conveyer structure and the doffing and stripping mechanisms.

Fig. 2 is a fragmentary elevation of the conveyer.

Fig. 3 is a section on the line 3—3 of Fig. 2.

Fig. 4 is a section on the line 4—4 of Fig. 2.

Fig. 5 is a perspective view of one of the spacer elements.

Fig. 6 is a view of one of the teeth.

In the illustrated embodiment characterizing this invention there is shown a hopper 1 adapted to contain a bulk of cotton to be elevated to a point adjacent its upper portion 2 for cleaning and other purposes by cotton machinery (not shown).

Mounted in hopper 1 is a pair of spaced horizontal rollers 3 and mounted on said rollers and adapted to travel in the direction of the arrow is an endless platform conveyer 4 having mounted on its outer surface suitable teeth or pins 5, and suitably journaled in hopper 1 adjacent end 6 is shaft 7 on which is mounted and suitably secured a roller 8. Suitably journaled in said hopper 1 adjacent the top thereof parallel to shaft 7 is shaft 9 having mounted thereon roller 10. Suitably mounted on rollers 8 and 9 adjacent their respective ends are sprocket wheels (not shown) adapted to drive the sprocket or link chains B constructed of sprocket links 11 formed at one end with a cylindrical bar 12 and at the other with a strap loop 13 in which is adapted to be inserted the bar portion 12 of an adjacent link 11. Each side portion 14 of the respective links 11 is formed with a lateral perforated ear 15 for a purpose directly appearing.

Adapted to bridge said chains B and with their ends supported by and connected to diametrically opposite links 11 are a plurality of channel supporting members 16. Each of said channel members 16 has its longitudinal edges bent upwardly and inwardly forming picker teeth retaining means 17 and forming said channel member into

a dovetail channel configuration 18 in cross section, as clearly shown in Fig. 3.

Adapted for slidable insertion in each of said dovetail channels 18 are a plurality of complementally formed intermediate spacer elements 19 and end spacer elements 20.

Each of the spacer elements 19 (Fig. 5) are formed with downwardly and outwardly side portions 21 extending at an angle corresponding to the inclined retaining walls 17 of channel member 16, said spacers adapted to be slidably engaged in the respective channel members 16 in end to end relation, contiguous spacers engaging opposite sides of a picker tooth member C to support said teeth against longitudinal movement with respect to said channel member.

Each of said picker teeth C is formed with a body portion 22 having an elongated base 23, the opposite edges 24 and 25 extending upwardly therefrom in meeting direction, said body portion terminating at its upper end in a substantially sharpened picker portion 26; said portion 26 extending substantially at right angles to the edge 25 and is adapted when the body portion 22 is transversely inserted in channel member 16 to project longitudinally of the conveyer and in its direction of travel.

Said body portion 22 adjacent its base 23 is formed to substantially correspond to channel member 16 and adapted when positioned between the meeting spacers to be supported in spaced relation against movement longitudinally of the channel member 16, the teeth of the respective channel members 16 being aligned. Adapted to be mounted in each end of the respective channel members 16 is an end spacer member 20 conforming at one end to the configuration of the intermediate channel members 19 and at the other end having the top portion 19a inclined downwardly as at 27 and terminating in a horizontal or flat end portion 28 adapted to engage the bottom of channel 16 to which it is secured by bolt 29 extending through ear 15 of one of the links 11, the opposite ear 15 being secured to the adjacent spacer 19 by bolt 30 extending through said spacer and block 31 mounted therein so as to prevent collapse of said spacer when bolt 19 is tightened as will be well understood. It will thus be seen that by this construction at each end the series of spacer elements 19 support and lock said teeth C against longitudinal movement with respect to each channel member and the retaining edges 17 forming the dovetail configuration 18 co-acts with the complementally formed body portion 22 of teeth C to support and lock them against movement transverse of said channel members and longitudinal of the conveyer A, as will be apparent.

It will be observed that each end of the respective channel members 16 is mounted on a link 11, and the inter-connection of said links form the chains B and at the same time the continuous conveyer A supported thereby, said conveyer presenting a series of parallelly arranged transverse rows of picker teeth C and including a series of spacer elements 16 in end to end relation, the picker teeth also being in longitudinal alignment with respect to the conveyer.

Suitably mounted in the hopper adjacent the delivery end of conveyer A is a doffing mechanism D formed with annular series of teeth 32, said doffing device adapted to rotate in the direction of the arrow and to remove the surplus cotton from the conveyer for return to the hopper. Mounted on the opposite side of the conveyer is a

stripper mechanism E having annular series of teeth 33 and adapted to rapidly rotate in the direction of the arrow to strip the cotton from the teeth C for delivery from the hopper and distribution to the further cotton treating mechanism (not shown).

With further reference to the arrangement and configuration of the picker teeth or fingers C, it will be noted that the spike-like teeth extending at right angles from the conveyer in the structures heretofore in use, for instance, as shown in the patent to Graves, No. 633,995, issued October 3, 1899, and Davis, No. 1,812,287, issued June 30, 1931, present certain disadvantages, and that the doffing mechanism in removing the surplus therefrom also frequently removes the entire quantity of cotton 34, as shown in Fig. 3, from the tooth, which should be carried up to the stripping mechanism E, and to overcome such deficiency and to effect a stronger tooth structure against breakage and distortion and to effect a better grabbing of and separation of the cotton from the bulk during the elevating travel of the conveyer, applicant designed the tooth structure C and mounting therefor (Fig. 3) by providing a truncated-like thin body portion 22, and formed at its upper end with the picker end 26 extending from the body portion at substantially right angles to the forward edge 25, and when engaged on opposite sides by the ends of the bracer elements 19 a strong, rigid unitary mounting and tooth structure is effected. The forward edge 25 forms a stop for the cotton gathered on said tooth and not only prevents the cotton as it is being picked from being forced to the base of the tooth but substantially carries the cotton spaced from said base and prevents the possibility of stripping of the teeth by the doffing mechanism and renders the cotton more easily stripped by the stripper mechanism, as will be apparent without further discussion.

While the operation of the device would seem to be clear from the above description it might be well to further state that initially the cotton is fed to the hopper and delivered by the platform conveyer to the elevating conveyer A, the picker points 26 of the teeth C penetrating the bulk in a substantially straight line, and the arcuate movement of said points separate quantities of cotton therefrom which is initially supported on shoulders 25 and when said cotton reaches the doffing mechanism D the surplus is removed and returned to the mass and the quantity remaining on the points 26 is carried to the stripper mechanism E where it is stripped therefrom for delivery from the hopper, as will be well understood.

It is apparent that I have designed an endless conveyer and tooth structure for the conveying of cotton, the teeth and mounting therefor adapted to withstand the strains and stresses incident to continued operation, such construction rendering it easy to assemble the components and install the device, which is simple in construction, manufacturable at a reasonable cost and efficient for the purposes intended.

While throughout the specification and claims the words "cotton," "cotton cleaner," "cotton handling machine," etc., have been referred to, it is to be understood that such terms wherever appearing are intended to likewise embrace wool and other fibers.

Although in practice I have found that the form of my invention illustrated in the accompanying drawing and referred to in the above

description as the preferred embodiment, is the most efficient and practical; yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A device of the character described comprising an endless conveyer consisting of hingedly connected transverse teeth supporting members, said transverse members having complementary teeth retaining means along their longitudinal edges, complementally formed spacer elements engageable in said retaining means interposed between said teeth, means for locking the end spacer members to said supports, whereby said teeth are braced both longitudinally and transversely of said conveyer.

2. A device of the character described comprising an endless conveyer consisting of a plurality of transverse predeterminedly formed channel supports, means for detachably and hingedly connecting said channel supports, picker teeth having their base supports correspondingly formed with respect to said channel supports adapted for insertion therein, spacer elements complementally formed with respect to said channel supports adapted to support said teeth, means for locking said spacer elements against movement longitudinal of said supports, whereby said teeth are locked against movement longitudinally and transversely of said conveyer.

3. A device of the character described comprising an endless conveyer consisting of a plurality of interconnected channel members having a dovetail configuration in cross section, a plurality of spacer elements complementally formed and engageable in said channel members, a plurality of picker teeth complementally formed at one end for insertion in said channel members and extending transversely thereof and longitudinally of said conveyer and interposed between said spacer members, the free ends of said teeth extending at an angle with respect to the body portions.

4. In a cotton handling machine, the combination with a feed hopper and doffing and stripping mechanisms at its upper end, of an endless conveyer co-operating at one end with said mechanisms and comprising hingedly connected transverse teeth supporting members, said transverse members having complementary teeth retaining means along their longitudinal edges, complementally formed spacer elements engageable in said retaining means interposed between said teeth, means for locking the end spacer members to said supports, whereby said teeth are braced both longitudinally and transversely of said conveyer.

5. In a cotton handling machine, the combination with a feed hopper and doffing and stripping mechanisms at its upper end, of an endless conveyer cooperating at its upper end with said mechanisms and comprising a plurality of transverse predeterminedly formed channel supports, means for detachably connecting said channel supports, picker teeth having their base portions correspondingly formed with respect to said channel supports adapted for

insertion therein, spacer elements complementally formed with respect to said channel supports adapted to support said teeth, means for locking said spacer elements against movement longitudinal of said supports, whereby said teeth are locked against movement longitudinally and transversely of said conveyer.

6. In a cotton handling machine, the combination with a feed hopper and doffing and stripping mechanisms at its upper end, of an endless conveyer co-operating with said mechanisms and comprising a plurality of interconnected channel members and having a dovetail configuration in cross section, a plurality of spacer elements complementally formed and engageable in said channel members, a plurality of picker teeth complementally formed at one end for insertion in said channel members and extending transversely thereof and longitudinally of said conveyer and interposed between said spacer members, the free ends of said teeth extending at an angle with respect to the body portions.

7. In a cotton handling machine the combination with a hopper, of a conveyer operatively mounted in the hopper, said conveyer comprising a plurality of transverse supports hingedly and detachably connected and having teeth retaining means, a series of picker teeth carried by each support, each of said teeth having an elongated base portion extending transversely of its support and longitudinal of the conveyer and co-acting with said retaining means to prevent its longitudinal movement with respect to said conveyer, said teeth having pointed portions extending at an angle therefrom in the direction of travel of the conveyer, and means co-acting with said supports to support the teeth against movement transversely of the conveyer.

8. A device of the character described including an endless conveyer comprising a plurality of inter-connected dovetail channel supports arranged in parallelism, a plurality of complementally formed spacer elements adapted for slideable engagement in said channels in end to end relation, a plurality of picker teeth each having a base portion corresponding in configuration to said channels and supportingly engageable therein, said teeth adapted to be supported between the meeting ends of said spacer elements, whereby said teeth are supported against movement longitudinally and transversely of said supports.

9. A device of the character described comprising an endless conveyer consisting of a plurality of channel supports, spacer elements arranged in said supports, a series of parallelly arranged picker teeth rows, each of said rows including spacer elements in end to end relation, a tooth being disposed between each of said elements, the configuration of the spacer elements and the base of the respective teeth conforming to that of said channel supports, the picker teeth of the respective rows being aligned.

10. A device of the character described comprising an endless conveyer including transverse supports formed with teeth retaining means along their longitudinal edges, non-yielding teeth complementally formed for individual detachable engagement with said supports and retaining means, and means to lock the respective teeth in spaced relation and prevent movement thereof laterally of said conveyer.
